UNITED STATES PATENT OFFICE

172,063

DESK CABINET OR THE LIKE

William A. Steinmetz, Lemay, Mo.

Application July 24, 1953, Serial No. 26,124

Term of patent 3½ years

(Cl. D74—1)

To all whom it may concern:

Be it known that I, William A. Steinmetz, a citizen of the United States, residing in Lemay, in the county of St. Louis and State of Missouri, have invented a new, original, and ornamental Design for a Desk Cabinet or the like, of which the following is a specification, reference being had to the accompanying drawing, forming a part thereof.

In the drawing:

Fig. 1 is a front perspective view of a desk cabinet showing my new design, and

Fig. 2 is a rear perspective view thereof.

I claim:

The ornamental design for a desk cabinet or the like, substantially as shown.
